Des. 215,286
Patented Sept. 23, 1969

215,286

SPRAY NOZZLE

George W. Meek, 1205 6th St., Page Park,
Fort Myers, Fla. 33901

Filed Feb. 21, 1968, Ser. No. 10,682

Term of patent 14 years

Int. Cl. D23—01

U.S. Cl. D23—34

FIG. 2

FIG. 1

FIG. 3

FIG. 4

FIG. 1 is an elevational view of a spray nozzle showing my new design;

FIG. 2 is a top plan view thereof;

FIG. 3 is a cross sectional view taken on line 3—3 of FIG. 2; and

FIG. 4 is an enlarged fragmentary perspective view thereof.

I claim:

An ornamental design for a spray nozzle, substantially as shown.
